UNITED STATES PATENT OFFICE

FRANCIS N. WOODMAN, OF CLINTON, MASSACHUSETTS, ASSIGNOR TO WICKWIRE
SPENCER STEEL COMPANY, OF NEW YORK, N. Y., A CORPORATION OF DELAWARE

FLANGED CONVEYER BELT

Application filed December 24, 1928. Serial No. 328,197.

This invention relates to a spiral wire belt of a type commonly used for transporting a wide variety of materials.

It is the general object of my invention to provide a conveyer belt of the spiral wire type so constructed that the carrying capacity thereof is materially increased.

A more specific object of my invention is to provide a spiral wire belt with upstanding flanges along the outer edges thereof, together with means for firmly supporting the flanges.

A further feature of my invention relates to the provision of means to prevent or substantially reduce transverse shrinkage in such a flanged conveyer belt.

My invention further relates to arrangements and combinations of parts which will be hereinafter described and more particularly pointed out in the appended claim.

A preferred form of the invention is shown in the drawings in which

Fig. 1 is a plan view of a portion of my improved belt;

Fig. 2 is an end elevation thereof; and

Fig. 3 is a diagrammatic view illustrating the manner of using my improved belt.

Referring to the drawings, I have shown a portion of a spiral wire belt B formed of interlaced spiral members 10 extending transversely of the belt and having their ends preferably looped together in pairs to form a selvage. The end portions of the spiral members 10 are bent upward out of the plane of the belt, and in the form shown in the drawings the upwardly bent members stand at an angle of substantially ninety degrees to the body of the belt. This provides an upstanding flange 11 along each edge of the belt, as indicated in Figs. 2 and 3, which may be of a desired and substantial height and which permits the belt to be used for transporting greatly increased loads of material M placed thereon.

In order that the upstanding flanges may

be firmly supported, I preferably insert cross rods 12 transversely of the belt and bend the end portions thereof upward with the spiral members, as clearly indicated in Fig. 2. The flanges 11 at both edges of the belt are thus firmly supported in definite spaced relation.

The cross rods 12 extend through the coils of certain of the spiral members 10 and are preferably inserted in and between two adjacent coils, as indicated in Fig. 1, so that the rod is engaged on opposite sides by the coils of two adjacent spiral members. When the belt is under tension, a strong frictional contact is developed, which prevents any substantial transverse shrinkage of the belt. Transverse shrinkage is also resisted by the upturned ends of the cross rods 12.

The cross rods 12 are inserted at spaced intervals along the belt and are preferably inserted in and between the coils of each successive pair of spiral members, as shown in Fig. 1. The spacing of the cross rods may be varied, however, to suit operating conditions.

Such flanged conveyer belts are useful for many different purposes and may be conveniently supported on spaced guide rolls 20, as indicated in Fig. 3. Such a flanged belt possesses greatly increased carrying capacity, but the construction is such that the flexibility of the belt is retained, so that it may be free to bend as it passes around pulleys or guide-rolls. This flexibility of the belt is increased by the fact that the ends of the spiral members are commonly looped together in adjacent pairs only, permitting substantial relative movement between adjacent pairs.

Having thus described my invention and the advantages thereof, I do not wish to be limited to the details herein disclosed otherwise than as set forth in the claim, but what I claim is:—

A spiral wire conveyer belt formed of a plurality of interlaced spiral wire members extending transversely of said belt, and a

plurality of cross rods extending transversely of said belt within said spiral members, the end portions of said members and cross rods being bent as a unit substantially perpendicular to the plane of said belt to provide and firmly support upstanding flanges of substantial height along the parallel side edges of said belt, effective to retain material during transportation thereon.

10 In testimony whereof I have hereunto affixed my signature.

FRANCIS N. WOODMAN.
